(57) **ABSTRACT**

A connection structure includes a housing; terminals fixed in the housing; and an electronic component accommodated inside the housing and connected to the terminals. Each terminal includes: a base portion; a protrusion piece extending from the base portion in a lateral direction; and an elastic contact piece extending from the base portion in the lateral direction so that a distance between the protrusion piece and the elastic contact piece becomes shorter towards an end of the elastic contact piece separate away from the base portion. The housing includes a terminal-fixing part protruded from a wall surface of the housing at a position between the protrusion piece and the elastic contact piece near the base portion of the terminal to clamp and fix the protrusion piece between the terminal-fixing part and a wall of the housing.

CONNECTION STRUCTURE OF ELECTRONIC COMPONENT

CROSS REFERENCE TO RELATED APPLICATIONS

This application is a continuation of PCT application No. PCT/JP2011/079126, which was filed on Dec. 9, 2011 based on Japanese Patent Application (No. 2010-286238) filed on Dec. 22, 2010, the contents of which are incorporated herein by reference.

BACKGROUND OF THE INVENTION

1. Field of the Invention

The present invention relates to a connection structure which electrically connects an electronic component by a terminal.

2. Description of the Related Art

In a connection structure of an electronic component (or an electronic-component connection structure) according to a related art which electrically connects electronic components by a pair of terminals, the pair of terminals are accommodated and fixed in a housing, and the electronic components are electrically connected by the pair of terminals. This electronic-component connection structure requires the reliability of the connection of the electronic components and the terminals. Therefore, an electronic-component connection structure which accurately positions electronic components with respect to terminals and connects the electronic components with the terminals has been proposed (see, for example, JP-2007-149762A).

The electronic-component connection structure disclosed in JP-2007-149762A is an electronic-component connection structure which is used for an electronic device and includes a housing, and terminals provided in the housing and having press-contact blades disposed to face each other for being electrically connected with electronic components for circuit protection by pressing, and in which a positioning rib is formed for positioning lead portions of the electronic components, disposed adjacent to the press-contact blades, toward the press-contact blades.

SUMMARY OF THE INVENTION

However, in the electronic-component connection structure disclosed in JP-2007-149762A, since locking portions are formed at the terminals to protrude in a vertical direction of the device, and the terminals are fixed at predetermined positions on the bottom surface of the housing by the locking portions, a thickness of the connection structure in its vertical direction increases, and thus it is difficult to make the connection structure thinner.

The present invention has been made considering the problem, and an object of the present invention is to provide an electronic-component connection structure capable of enabling a reduction in thickness.

According to a first aspect of the present invention, there is provided a connection structure, including: a box-shaped housing having at least side walls which face each other; a pair of terminals which are inserted into the housing to be fixed inside the housing vertically in parallel to planes of the side walls; and an electronic component which is accommodated inside the housing by being connected to the pair of terminals, wherein each terminal of the pair of terminals includes: a base portion; a protrusion piece extending from the base portion in a lateral direction parallel to a bottom

2

plane and the planes of the side walls of the housing; and an elastic contact piece extending from the base portion in the lateral direction so that a distance between the protrusion piece and the elastic contact piece becomes shorter towards an end of the elastic contact piece separate away from the base portion, wherein the housing includes a terminal-fixing part which is protruded from a wall surface of the housing at a position between the protrusion piece and the elastic contact piece near the base portion of the terminal when the terminal is inserted into the housing to clamp and fix the protrusion piece between the terminal-fixing part and one of a bottom wall or an upper wall of the housing.

A second aspect of the present invention provides the connection structure, wherein the terminal-fixing part is formed on a wall surface of the side walls of the housing.

A third aspect of the present invention provides the connection structure, wherein the housing includes a separation wall which divides an accommodation space in the housing into two accommodation spaces in which the pair of terminals are accommodated, respectively, and the terminal-fixing part is formed on a wall surface of the separation wall of the housing.

A fourth aspect of the present invention provides the connection structure, wherein the housing opens at an upper face, and the protrusion piece is clamped and fixed between the terminal-fixing part and the bottom wall of the housing.

A fifth aspect of the present invention provides the connection structure, wherein the terminal-fixing part includes an inclined surface having an upper end and a lower end which is closer to the bottom wall than the upper end, the lower end of the inclined surface being more separate away from the wall surface than the upper end.

According to the electronic-component connection structure in the first aspect of the present invention, each terminal of the pair of terminals is not required to protrude a fixing means in a vertical direction, and it is possible to fix the terminals in the housing by effectively using the dead space between the protrusion pieces and the contact pieces. Therefore, it is possible to fix the terminals in the housing without increasing a dimension in the vertical direction, and thus reduce the thickness.

Further, according to the electronic-component connection structure in the second aspect of the present invention, since the terminal-fixing part is formed at the side surface of the housing, it is possible to fix the terminals in the housing without increasing the dimension in the vertical direction.

Further, according to the electronic-component connection structure in the third aspect of the present invention, since the terminal-fixing part is formed at the surface of separation wall which divides the housing into two accommodation spaces, it is possible to fix the terminals in the housing without increasing the dimension in the vertical direction.

Furthermore, according to the electronic-component connection structure in the fourth aspect of the present invention, since the housing has an opened upper face, and the terminal-fixing parts clamp the protrusion pieces in cooperation with the bottom wall of the housing, it is not necessary to provide a wall at the upper face of the housing for fixing the terminals. Therefore, it is possible to fix the terminals in the housing without increasing a dimension in the vertical direction, and thus reduce the thickness.

Moreover, according to the electronic-component connection structure in the fifth aspect of the present invention, since each terminal-fixing part has the inclined surface having an upper end and a lower end which is closer to the bottom wall than the upper end, the lower end of the inclined surface being more separate away from the wall surface than the upper end, when each terminal of the pair of terminals is accommodated

from over the housing into the housing, it is possible to easily dispose the protrusion pieces between the terminal-fixing part and the wall forming the bottom wall of the housing.

BRIEF DESCRIPTION OF THE DRAWINGS

FIG. 1 is an exploded perspective view illustrating a configuration of an LED lighting unit having an electronic-component connection structure according to an embodiment of the present invention.

FIG. 2 is a top view of the LED lighting unit with an electric-wire holding part in FIG. 1 removed.

FIG. 3 is a cross-sectional view of the LED lighting unit shown in FIG. 2 as taken along line A-A.

FIG. 4 is a cross-sectional view of the LED lighting unit shown in FIG. 2 as taken along line B-B.

FIG. 5 is a bottom view of the electronic-component connection structure shown in FIG. 1.

FIG. 6 is an enlarged perspective view of a housing shown in FIG. 1.

FIG. 7 is a cross-sectional view illustrating a portion of the housing shown in FIG. 6.

FIG. 8 is an enlarged perspective view of a terminal shown in FIG. 1.

FIG. 9 is a diagram for explaining details of the electric-wire holding part shown in FIG. 1.

FIG. 10 is a circuit diagram illustrating a circuit configuration of the LED lighting unit shown in FIG. 1.

FIG. 11 is a diagram for illustrating an assembly procedure of the LED lighting unit having the electronic-component connection structure according to the embodiment of the present invention.

FIG. 12 is a diagram for illustrating the assembly procedure of the LED lighting unit having the electronic-component connection structure according to the embodiment of the present invention.

FIG. 13 is a diagram for illustrating the assembly procedure of the LED lighting unit having the electronic-component connection structure according to the embodiment of the present invention.

FIG. 14 is a diagram for illustrating the assembly procedure of the LED lighting unit having the electronic-component connection structure according to the embodiment of the present invention.

FIG. 15 is a diagram for illustrating the assembly procedure of the LED lighting unit having the electronic-component connection structure according to the embodiment of the present invention.

FIG. 16 is a diagram for illustrating a modification of the electronic-component connection structure according to the embodiment of the present invention.

DETAILED DESCRIPTION OF THE EXEMPLARY EMBODIMENTS

Hereinafter, a connection structure of an electronic component (or an electronic-component connection structure) according to an embodiment of the present invention will be described in detail with reference to the accompanying drawings.

Embodiment

FIG. 1 is an exploded perspective view illustrating a structure of an LED lighting unit 100 having an electronic-component connection structure 1 according to an embodiment of the present invention. FIG. 2 is a top view of the LED lighting

unit 100 with an electric-wire holding part 120 in FIG. 1 removed. FIG. 3 is a cross-sectional view of the LED lighting unit 100 shown in FIG. 2 as taken along line A-A. FIG. 4 is a cross-sectional view of the LED lighting unit 100 shown in FIG. 2 as taken along line B-B. FIG. 5 is a bottom view of the electronic-component connection structure 1 shown in FIG. 1. FIG. 6 is an enlarged perspective view of a housing 10 shown in FIG. 1. FIG. 7 is a cross-sectional view illustrating a portion of the housing 10 shown in FIG. 6. FIG. 8 is an enlarged perspective view of a terminal 20 shown in FIG. 1. FIG. 9 is a diagram for explaining details of the electric-wire holding part 120 shown in FIG. 1. FIG. 10 is a circuit diagram illustrating a circuit configuration of the LED lighting unit 100 shown in FIG. 1.

15 In FIGS. 1 to 10, for convenience, arrow directions are defined as a front side, a rear side, an upper side, and a lower (down) side.

The LED lighting unit 100 having the electronic-component connection structure 1 according to the embodiment of 20 the present invention performs light irradiation of an LED element L by electrically connecting two electric wires with a pair of terminals 20. The LED lighting unit 100 includes a unit housing 110, the electronic-component connection structure 1, and the electric-wire holding part 120, as shown in FIG. 1.

25 First, the unit housing 110 will be described. The unit housing 110 accommodates the electronic-component connection structure 1 and the electric-wire holding part 120. The unit housing 110 is a casing having an opening 110a serving as an insertion opening for accommodating the electronic-component connection structure 1 and the electric-wire holding part 120 within the unit housing 110. Inside the unit housing 110, the electronic-component connection structure 1 and the electric-wire holding part 120 are disposed in the order of the electronic-component connection structure 1 and the electric-wire holding part 120 from the front side. Further, the unit housing 110 includes an opening 111 for illumination and an opening 112 for engagement.

30 The opening 111 for illumination is an opening formed at a wall forming an upper face of the unit housing 110, and is 40 for emitting light emitted from the LED element L accommodated within the unit housing 110 toward the outside. The opening 111 for illumination may have a structure for enabling a light transmissive member such as a lens to be used as a lid.

45 The opening 112 for engagement is an opening formed at a side wall of the unit housing 110 in the vicinity of the opening 110a. The opening 112 for engagement is engaged with a lance portion 122 (to be described below) of the electric-wire holding part 120. In other words, the opening 112 for engagement can be engaged with the lance portion 122 so as to fix the electronic-component connection structure 1 and the electric-wire holding part 120 within the unit housing 110.

50 Next, the electronic-component connection structure 1 will be described. The electronic-component connection structure 55 1 includes the housing 10, and a pair of terminals 20 that is accommodated within the housing 10. The electronic-component connection structure 1 is for electrically connecting electronic components accommodated inside the housing 10 by the pair of terminals 20 fixed within the housing 10. In 60 other words, the electronic-component connection structure 1 electrically connects the LED element L, a Zener diode D, and a resistor R as electronic components, and accommodates the LED element L, the Zener diode D, and the resistive plate R within the housing 10. In a case where the electronic-component connection structure 1 is accommodated within the unit housing 110, as shown in FIG. 3, the LED element L is disposed at a position corresponding to the opening 111 for

illumination, and press-contact terminal portions **23b** (to be described below) to be connected with individual electric wires **W** are directed toward the opening **110a** of the unit housing **110**.

The housing **10** is a casing which is made of an insulating material to have an opening **10a** at the upper face thereof. The housing **10** includes a rectangular bottom wall **11**, and a front wall **12**, a rear wall **13**, and a pair of side walls **14** provided to stand from four sides of the bottom wall **11**, as shown in FIGS. 5 to 7. The rear wall **13** faces the front wall **12**, and the pair of side walls **14** faces each other. Further, the housing **10** includes an LED-element insertion opening **12a**, a Zener-diode insertion opening **12b**, a resistive-plate insertion opening **11a**, a separation wall **15**, and a terminal-fixing part **16**.

The LED-element insertion opening **12a** is an opening formed at the front wall **12** for inserting the LED element **L** into the housing **10**.

The Zener-diode insertion opening **12b** is an opening formed at the front wall **12** for inserting the Zener diode **D** into the housing **10**.

The resistive-plate insertion opening **11a** is an opening formed at the bottom wall **11** for inserting the resistive plate **R** into the housing **10**.

The separation wall **15** is a wall which is provided at a position between the side walls **14** facing each other to stand from the bottom wall **11** in parallel with the side walls **14** and divides the accommodation space in the housing **10** into two accommodation spaces almost equal to each other. The two accommodation spaces in the housing **10** accommodate corresponding terminals **20**. Therefore, the terminals **20** are accommodated within the housing **10** while maintaining an insulation state without being in contact with each other.

In a wall surface of the separation wall **15** and a side surface of the side walls **14** facing the corresponding wall surface of the separation wall **15**, a pair of straight grooves **15a** is formed in a vertical direction, and functions as a guide for disposing the resistive plate **R** at a connection position of a corresponding terminal **20** in the housing **10**.

Further, at positions of a front end portion of the separation wall **15** corresponding to the LED-element insertion opening **12a** and the Zener-diode insertion opening **12b**, notch portions **15b** are formed to allow the LED element **L** and the Zener diode **D** to be accommodated within the housing **10**.

The terminal-fixing part **16** is formed to protrude from a wall surface **15c** of the separation wall **15** as shown in FIG. 3, and clamps the terminals **20** in cooperation with the bottom wall **11** of the housing **10** so as to fix each terminal **20** in the housing **10**.

Next, the terminals **20** will be described.

Each terminal **20** is formed integrally by a pressing work on a conductive plate-shaped member. As shown in FIG. 8, each terminal **20** includes a first component-connection portion **21** and a second component-connection portion **22** formed by bending both longitudinal sides of a rectangular top board portion **20a** downward, and an electric-wire connection portion **23** formed by bending a rear end portion of the top board portion **20a** downward and then bending the rear end portion toward the rear side. The top board portion **20a** includes a pair of bent edge portions **20b** formed by bending both edges, forming the both longitudinal edges of the top board portion **20a**, downward.

The first component-connection portion **21** includes a pair of base portions **21a** provided to stand from both edge of the top board portion **20a**, a pair of protrusion pieces **21b** extending from lower edges of the base portions **21a** toward the front side (in a lateral direction), and a pair of first contact pieces **21c** and a pair of second contact pieces **21d** protruding from

the base portions **21a** between the top board portion **20a** and the pair of protrusion pieces **21b** toward the front side (in the lateral direction).

The pair of first contact pieces **21c** extends toward end portions **21cc** to shorten distances from the top board portion **20a**. The pair of first contact pieces **21c** has elasticity.

The pair of second contact pieces **21d** is formed below the pair of first contact pieces **21c** to extend toward end portions **21dd** such that distances from the protrusion pieces **21b** are shortened. The pair of second contact pieces also has elasticity.

Each first contact piece **21c** having this structure includes an LED-element connection portion **24** to be electrically connected with the LED element **L**, and a Zener-diode connection portion **25** to be electrically connected with the Zener diode **D**.

The LED-element connection portion **24** clamps the LED element **L** by the pair of bent edge portions **20b** of the top board portion **20a** and the pair of first contact pieces **21c**. In other words, the LED element **L** is inserted between the pair of bent edge portions **20b** and the pair of first contact pieces **21c**, such that the LED element **L** is clamped by the elasticity of the pair of first contact pieces **21c**, and the pair of terminals **20** and the LED element **L** are electrically connected.

The Zener-diode connection portion **25** clamps the Zener diode **D** by the pair of protrusion pieces **21b** and the pair of second contact pieces **21d**. In other words, the Zener diode **D** is inserted between the pair of protrusion pieces **21b** and the pair of second contact pieces **21d**, such that the Zener diode **D** is clamped by the elasticity of the pair of second contact pieces **21d** and the pair of terminals **20** and the Zener diode **D** are electrically connected.

The second component-connection portion **22** includes a pair of base portions **21a**, and a pair of engagement portions **22a** and a pair of third contact pieces **22d** provided to stand from both edges of the top board portion **20a**.

The pair of engagement portions **22a** includes main end surface portions **22b** and hook-like portions **22c**.

The main end surface portions **22b** have end surfaces formed to extend vertically. In a case where the terminals **20** are accommodated within the housing **10**, the main end surface portions **22b** are brought into surface-contact with an inner surface of the rear wall **13** as shown in FIG. 3.

The hook-like portions **22c** are portions formed in a hook shape at lower portions of the engagement portions **22a**. In the case where the terminals **20** are accommodated within the housing **10**, the hook-like portions **22c** are engaged with an inner-surface-side step **13a** formed on the inner surface side of the rear wall **13**, as shown in FIG. 3.

The pair of third contact pieces **22d** is a pair of elastic pieces extending from the top board portion **20a** between the pair of base portions **21a** and the pair of engagement portions **22a** downward, as shown in FIG. 8. The pair of third contact pieces **22d** extends toward the end portions to shorten distances from the pair of base portions **21a**.

The second component-connection portion **22** having the above-mentioned structure includes a resistive-plate connection portion **26** to be electrically connected with the resistive plate **R**.

The resistive-plate connection portion **26** clamps the resistive plate **R** by the pair of base portions **21a** and the pair of third contact pieces **22d**. In other words, the resistive plate **R** is inserted between the pair of base portions **21a** and the pair of third contact pieces **22d**, such that the resistive plate **R** is clamped by the elasticity of the pair of third contact pieces **22d** and the terminals **20** and the resistive plate **R** are electrically connected.

The electric-wire connection portion 23 includes a wall-surface contact portion 23a and a press-contact terminal portion 23b. The wall-surface contact portion 23a is a portion formed by bending the top board portion 20a downward. The wall-surface contact portion 23a is formed in a bent shape along an outer surface including an upper end surface of the rear wall 13 when the terminals 20 are accommodated within the housing 10, as shown in FIG. 3.

The press-contact terminal portion 23b is a portion formed by bending from the downwardly-bent wall-surface contact portion 23a toward the rear side, as shown in FIG. 8. The press-contact terminal portion 23b has a notch 23c formed in a U shape. When the electric wire W is pressed into the notch 23c, the electric wire W and the terminals 20 are electrically connected.

A bent portion serving as a boundary between the wall-surface contact portion 23a and the press-contact terminal portion 23b is formed to be engaged with an outer-surface-side step 13b formed at the rear wall 13, as shown in FIG. 3. Therefore, the terminals 20 clamp the rear wall 13 by the wall-surface contact portion 23a and the pair of engagement portions 22a.

Now, the terminal-fixing parts 16 will be described in more detail.

The terminal-fixing parts 16 are formed to protrude from the side surface of the separation wall 15 at the vicinities of the pair of base portions 21a between the pair of protrusion pieces 21b and the pair of second contact pieces 21d of each terminal 20 when each terminal 20 of the pair of terminals 20 is accommodated within the housing 10, as shown in FIG. 3, and clamp the protrusion pieces 21b in cooperation with the bottom wall 11 of the housing 10 so as to fix each terminal 20 within the housing 10.

More specifically, the terminal-fixing parts 16 are formed to protrude from both side surfaces of the separation wall 15 into the two accommodation spaces of the housing 10, as shown in FIG. 7. Further, each terminal-fixing part 16 includes an inclined surface 16a having an upper end and a lower end which is closer to the bottom wall, the lower end of the inclined surface being more separate away from the separation wall 15 than the upper end. Each terminal-fixing part 16 further includes a lower end surface 16b which is a flat surface having a normal line oriented in the vertical direction. Therefore, in the case where the terminals 20 are accommodated within the housing 10, as shown in FIG. 3, the pair of protrusion pieces 21b is clamped and fixed between the terminal-fixing part 16 and the bottom wall 11 at positions between the lower end surface 16b of the terminal-fixing part 16 and the upper surface of the bottom wall 11.

Although the pair of second contact pieces 21d extend such that the distances from the protrusion pieces 21b are shortened toward the end portions 21dd, since the terminal-fixing parts 16 are disposed in dead spaces which are in the vicinities of the base portions 21a and where the second contact pieces 21d and the protrusion pieces 21b are distant from each other, the terminal-fixing parts 16 and the second contact pieces 21d do not interfere with each other.

Next, the electric-wire holding part 120 will be described.

The electric-wire holding part 120 holds a bent portion of each electric wire W formed by turning each electric wire W back, and is accommodated within the unit housing 110 in that state, as shown by (a) to (b) in FIG. 9, so as to electrically connect each electric wire W to each terminal 20 in the unit housing 110.

The electric-wire holding part 120 holds two electric wires W to be electrically connected to each terminal 20 of the pair

of terminals 20. Further, the electric-wire holding part 120 includes a bend-holding portion 121 and the lance portion 122.

The bend-holding portion 121 is for holding the bent portion of each electric wire W formed by turning each electric wire W back. The bend-holding portion 121 is formed to be inserted into the unit housing 110 up to a position at which the bent portion of each electric wire W is brought into contact with each press-contact terminal portion 23b by pressurizing. Further, the bend-holding portion 121 includes notches 121a formed at the front end portion such that the press-contact terminal portions 23b are connected to the electric wires W.

The lance portion 122 is engaged with engagement openings 112 formed at the unit housing 110 so as to fix the electric-wire holding part 120 within the unit housing 110.

The electric-wire holding part 120 bends and holds each electric wire W, and then is accommodated within the unit housing 110, such that the pair of press-contact terminal portions 23b are electrically connected to the corresponding electric wires W.

The LED lighting unit 100 having the above-mentioned configuration is configured by connecting the LED element L and the Zener diode D in parallel as shown in FIG. 10, such that the LED element L is protected from an over-voltage.

Next, an assembly procedure of the LED lighting unit 100 having the electronic-component connection structure 1 according to the embodiment of the present invention will be described with reference to FIGS. 11 to 15. FIGS. 11 to 15 are diagrams for illustrating an assembly procedure of the LED lighting unit 100 having the electronic-component connection structure 1 according to the embodiment of the present invention.

First, a worker accommodates the pair of terminals 20 within the housing 10, as shown in FIG. 11. At this time, each terminal 20 is inserted from the opening 10a of the housing 10. In this case, each terminal 20 smoothly moves the wall surfaces of the protrusion pieces 21b on the separation wall 15 side while bringing into contact with the wall surfaces with the inclined surfaces 16a of the terminal-fixing parts 16, and is fixed in the housing 10 such that the protrusion pieces 21b are positioned between the lower end surface 16b of the terminal-fixing part 16 and the upper surface of the bottom wall 11.

Then, the worker connects the LED element L and the Zener diode D to the pair of terminals 20 as shown in FIG. 12. More specifically, the LED element L is inserted from the LED-element insertion opening 12a into the housing 10, and is disposed between the pair of bent edge portions 20b and the pair of the first contact pieces 21c. At this time, the LED element L is inserted while widening gaps between the pair of bent edge portions 20b and the pair of first contact pieces 21c by using the elasticity of the pair of first contact pieces 21c. Therefore, a biasing force is applied toward the pair of bent edge portions 20b by the pair of first contact pieces 21c, such that the LED element L is held between the pair of bent edge portions 20b and the pair of first contact pieces 21c, as shown in FIG. 3.

The Zener diode D is inserted from the Zener-diode insertion opening 12b, and is disposed between the pair of protrusion pieces 21b and the pair of second contact pieces 21d. At this time, the Zener diode D is inserted while widening gaps between the pair of protrusion pieces 21b and the pair of second contact pieces 21d by using the elasticity of the pair of second contact pieces 21d. Therefore, a biasing force is applied toward the pair of protrusion pieces 21b by the pair of second contact pieces 21d, such that the Zener diode D is held

between the pair of protrusion pieces **21b** and the pair of second contact pieces **21d**, as shown in FIG. 3.

Next, the worker connects the resistive plate **R** to the pair of terminals **20** as shown in FIG. 13. At this time, the resistive plate **R** is inserted from the resistive-plate insertion opening **11a** into the housing **10** while being guided by the pair of grooves **15a**, and is disposed between the pair of base portions **21a** and the pair of third contact pieces **22d**. Further, the resistive plate **R** is inserted while widening gaps between the base portions **21a** and the pair of third contact pieces **22d** by using the elasticity of the pair of third contact pieces **22d**. Therefore, a biasing force is applied toward the pair of base portions **21a** by the pair of third contact pieces **22d**, such that the resistive plate **R** is held between the pair of base portions **21a** and the pair of third contact pieces **22d**, as shown in FIG. 3.

By the above-mentioned assembly work, the electronic-component connection structure **1** is completed.

Next, the worker accommodates the electronic-component connection structure **1** within the unit housing **110** as shown in FIG. 14. Therefore, the LED element **L** is disposed at a position corresponding to the opening **111** for illumination of the unit housing **110**. Further, the press-contact terminal portions **23b** of the pair of terminals **20** are disposed toward the opening **110a** side of the unit housing **110**.

Next, the worker accommodates the electric-wire holding part **120** within the unit housing **110** as shown in FIG. 15. In this way, the LED lighting unit **100** is completed. When the electric-wire holding part **120** is pressed from the opening **110a** of the unit housing **110** up to a predetermined position in the unit housing **110**, each electric wire **W** is pressed into the notch **23c** of each press-contact terminal portion **23b**, such that each electric wire **W** and a corresponding terminal **20** are electrically connected. As described above, since the lance portions **122** are engaged with the engagement openings **112** of the unit housing **110** with each electric wire **W** and a corresponding terminal **20** electrically connected, the electric-wire holding parts **120** are fixed in the unit housing **110** in a state in which the connection of each electric wire **W** and a corresponding terminal **20** is maintained.

According to the electronic-component connection structure **1** in the embodiment of the present invention, each terminal **20** is not required to protrude a fixing means in a vertical direction, and it is possible to fix each terminal **20** in the housing **10** by effectively using the dead spaces between the pair of protrusion pieces **21b** and the pair of second contact pieces **21d**. Therefore, it is possible to fix each terminal **20** in the housing **10** without increasing a dimension in the vertical direction, and thus reduce the thickness.

Further, according to the electronic-component connection structure **1** in the embodiment of the present invention, since the terminal-fixing part **16** is formed at the side surface **15a** of the separation wall **15**, it is possible to fix each terminal **20** in the housing **10** without increasing the dimension in the vertical direction.

Furthermore, according to the electronic-component connection structure **1** in the embodiment of the present invention, since the housing **10** has an opened upper face, and the terminal-fixing parts **16** clamp the pair of protrusion pieces **21b** of each terminal **20** in cooperation with the bottom wall **11** of the housing **10**, it is possible to fix each terminal **20** in the housing **10** without providing a wall at the upper face of the housing **10**, and thus reduce the thickness.

Moreover, according to the electronic-component connection structure **1** in the embodiment of the present invention, since each terminal-fixing part **16** has the inclined surface **16a** having an upper end and a lower end which is closer to the

bottom wall, the lower end of the inclined surface being more separate away from the separation wall **15** than the upper end, when each terminal **20** is accommodated from over the housing **10** into the housing **10**, it is possible to easily dispose the protrusion pieces **21b** between the terminal-fixing part **16** and the bottom wall **11**.

Modification

Now, a modification of the electronic-component connection structure **1** in the embodiment of the present invention will be described with reference to FIG. 16. FIG. 16 is a diagram for illustrating a modification of the electronic-component connection structure **1** in the embodiment of the present invention.

In the electronic-component connection structure **1** of the embodiment of the present invention, the terminal-fixing parts **16** clamp the terminals **20** in cooperation with the bottom wall **11** of the housing **10**. However, in an electronic-component connection structure **2** according to the modification, terminal-fixing parts **18** clamp the terminals **20** in cooperation with an upper wall **17** forming the upper face of the housing **10**.

The terminal-fixing parts **18** are formed to protrude at the vicinities of the pair of base portions **21a** from the side surfaces of the separation wall **15** between the top board portion **20a** of each terminal **20** and the pair of first contact pieces **21c** in the case where each terminal **20** of the pair of terminals **20** is accommodated within the housing **10**. The terminal-fixing part **18** clamps the top board portion **20a** in cooperation with the upper wall **17** of the housing **10**, and fixes each terminal **20** in the housing **10**. In other words, the top board portion **20a** extends from the base portion **21a** in the horizontal direction, so as to have the same function as that of the protrusion pieces **21b**. Therefore, according to the electronic-component connection structure **2** in this modification, similarly to the electronic-component connection structure **1** of the embodiment, it is possible to fix each terminal **20** in the housing **10** without increasing the dimension in the vertical direction, and thus reduce the thickness.

Further, the upper wall **17** in this modification may be formed partly at the upper face of the housing **10** as long as the upper wall **17** can clamp the terminals **20** in cooperation with the terminal-fixing part **18**.

Furthermore, more preferably, the terminals **20** may be formed such that vertical thicknesses of portions of the terminals **20** to be clamped by the terminal-fixing parts **16** are small. In this case, even if the upper wall **17** is provided, the thickness in the vertical direction does not increase.

In the electronic-component connection structure **1** according to the embodiment of the present invention, one pair of terminals **20** is used. However, the present invention is not limited thereto. In other words, two or more terminals to be electrically connected to electronic components may be provided.

In the electronic-component connection structure **1** according to the embodiment of the present invention, each terminal **20** is formed by pressing on the plate-shaped member. However, the present invention is not limited thereto. In other words, each terminal may include a base portion **21a**, a protrusion piece **21b** or a top board portion **20a** extending from the base portion **21a** in a lateral direction, and a contact piece which extends in the lateral direction such that a distance from the protrusion piece **21b** or the top board portion **20a** decreases from the base portion **21a** toward an end portion, and has elasticity.

11

In the electronic-component connection structure 1 according to the embodiment of the present invention, the terminal-fixing parts 16 are formed at the side surfaces of the separation wall 15. However, the present invention is not limited thereto. In other words, each terminal 20 may be formed to protrude from the wall surface of the housing 10 in the vicinity of the pair of base portions 21a between the pair of protrusion pieces 21b and the pair of second contact pieces 21d in a case where each terminal 20 is accommodated in the housing 10. For example, the terminal-fixing parts 16 may be formed at the side walls 14.

In the electronic-component connection structure 1 according to the embodiment of the present invention, as the electronic components, the LED element L, the Zener diode D, and the resistive plate R are electrically connected to the pair of terminals 20. However, the present invention is not limited thereto. In other words, other electronic components may be connected to the pair of terminals 20.

The present invention is not limited by the embodiment and the modification as mentioned above.

What is claimed is:

1. A connection structure, comprising:
a box-shaped housing having at least side walls which face each other;
a pair of terminals which are inserted into the housing to be fixed inside the housing vertically in parallel to planes of the side walls; and
an electronic component which is accommodated inside the housing by being connected to the pair of terminals, wherein each terminal of the pair of terminals includes:
a base portion;
a protrusion piece extending from the base portion in a lateral direction parallel to a bottom plane and the planes of the side walls of the housing; and

12

an elastic contact piece extending from the base portion in the lateral direction so that a distance between the protrusion piece and the elastic contact piece becomes shorter towards an end of the elastic contact piece separate away from the base portion,

wherein the housing includes a terminal-fixing part which is protruded from a wall surface of the housing at a position between the protrusion piece and the elastic contact piece near the base portion of the terminal when the terminal is inserted into the housing to clamp and fix the protrusion piece between the terminal-fixing part and one of a bottom wall or an upper wall of the housing.

2. The connection structure according to claim 1, wherein the terminal-fixing part is formed on a wall surface of the side walls of the housing.

3. The connection structure according to claim 1, wherein the housing includes a separation wall which divides an accommodation space in the housing into two accommodation spaces in which the pair of terminals are accommodated, respectively, and

the terminal-fixing part is formed on a wall surface of the separation wall of the housing.

4. The connection structure according to claim 1, wherein the housing opens at an upper face, and the protrusion piece is clamped and fixed between the terminal-fixing part and the bottom wall of the housing.

5. The connection structure according to claim 4, wherein the terminal-fixing part includes an inclined surface having an upper end and a lower end which is closer to the bottom wall than the upper end, the lower end of the inclined surface being more separate away from the wall surface than the upper end.
